UNITED STATES PATENT OFFICE.

WILLIAM H. SHOCK, OF BALTIMORE, MARYLAND.

IMPROVEMENT IN STEAM-HEATERS.

Specification forming part of Letters Patent No. 158,136, dated December 22, 1874; application filed December 4, 1874.

To all whom it may concern:

Be it known that I, WILLIAM H. SHOCK, of Baltimore, in the county of Baltimore and State of Maryland, have invented certain new and useful Improvements in Steam-Radiators; and I do hereby declare that the following is a full, clear, and exact description thereof, which will enable others skilled in the art to which it pertains to make and use the same, reference being had to the accompanying drawings, and to the letters of reference marked thereon, which form a part of this specification.

My invention relates to that class of steam-radiators in which one or more series of vertical pipes are arranged upon a base or condensing box, the pipes of each series being connected by means of U-shaped connections at their ends; and it consists in an improvement in radiators where a water-seal is used at the bottom of the pipes, in providing a device allowing the steam free circulation, yet furnishing means for the escape of the condensed steam, while the main current of steam does not come in contact with the water in the box, thus preventing condensation to a great extent.

This is accomplished by means of providing the lower connections with a siphon, bent tube, or its equivalent, to form a water-seal, whereby the steam is prevented from going directly into the box, and keeping the same in continuous circulation, and the condensed steam is allowed to flow into the box, as will be hereinafter more fully described, and pointed out by the claim.

In the annexed drawing, Figure 1 is a longitudinal section of a steam-radiator embodying my invention. Fig. 2 is an end view of the same; and Fig. 3 is an enlarged vertical section through one of the bottom connections.

A represents the base or condensing box, provided at one end with a waste-pipe, a. Upon the base A are placed one or more series of vertical pipes, B B, the pipes of each series being connected at their upper ends by inverted U-shaped connections C C, and at their lower ends by U-shaped connections D D, so as to form a continuous pipe for the passage of the steam, the last pipe of each series, however, reaching down into the box A. E represents the steam-pipe from the

boiler, conveying steam into a T-pipe, G, which is connected with the first pipe, B, in each series of vertical pipes; and in each of said connections is a globe valve, b, by the use of which the steam may be made to pass through either of the series of pipes, or through as many of them as may be desired. The steam thus admitted passes through all the pipes in the series, and through the last one into the box A.

The condensed steam in the pipes is allowed to escape into the box through a siphon, or its equivalent, attached to a projection, x, in the center of each of the U-shaped connections D, through the top of the box. To prevent the egress of the steam through these apertures x is the object of my invention; and to this end I apply a small siphon, d, or its equivalent, under each of said apertures within the box A.

As the steam condenses in the pipes the water passes through the apertures x into the siphons d, filling them, and forming water-seals, which effectually prevent the escape of steam, through said apertures, into the box.

Of course, after the siphons are filled, the excess of condensed steam will pass into the box A. The steam thus has a free and continuous passage through all the pipes of the series, and passes through the last one only into the box, and becomes condensed, the water being drawn off from said box through the waste-pipe a.

Having thus fully described my invention, what I claim as new, and desire to secure by Letters Patent, is—

In a steam-radiator consisting of one or more series of vertical pipes, B, connected by means of U-shaped connections C D, and arranged upon a condensing-box, A, the siphons d, arranged under the centers of the lower U-shaped connections D, to form water-seals, and prevent the passage of steam from the pipes into the box, all combined substantially as herein set forth.

In testimony that I claim the foregoing as my own I affix my signature in presence of two witnesses.

WILLIAM H. SHOCK.
